UNITED STATES PATENT OFFICE

164,892

COMBINED SERVING TRAY AND FOOD CONTAINERS OR SIMILAR ARTICLE

John C. Baker, Columbus, Ohio

Application June 15, 1950, Serial No. 10,529

Term of patent 14 years

(Cl. D44—10)

To all whom it may concern:

Be it known that I, John C. Baker, a citizen of the United States, residing in the city of Columbus, county of Franklin, and State of Ohio, have invented a new, original, and ornamental Design for a Combined Serving Tray and Food Containers or Similar Article, of which the following is a specification, reference being had to the accompanying drawing forming a part thereof.

In the drawing:

Fig. 1 is a perspective view of a combined serving tray and food containers or similar article, showing my new design;

Fig. 2 is a medial cross section of the same, taken along line 2—2 of Fig. 1 looking in the direction of the arrows.

The entire assembly is symmetrical about a vertical plane through line 2—2, except that the pouring spout shown in Fig. 1 is not present on the rear face opposite the spout. The appearance

of the combination from the rear is, therefore, exactly like Fig. 1, except that where the spout appears in Fig. 1 there appears in the view from the rear merely a continuation of the surrounding vertical plane surface to the height of the rest of the same surface.

I claim:

The ornamental design for a combined serving tray and food containers or similar article, substantially as shown and described.

JOHN C. BAKER.
